UNITED STATES PATENT OFFICE

HUGO BROCK, OF BERLIN, GERMANY

BOAT

Application filed August 16, 1927, Serial No. 213,329, and in Germany August 20, 1926.

My invention relates to boats, and it is an object of my invention to provide means for preventing the entrapping of persons in the boat when it capsizes.

To this end I provide a deck which will open automatically under the action of gravity when the boat capsizes.

In a preferred embodiment of my invention I provide a deck which is subdivided 10 preferably on the fore-and-aft line of the boat and the parts of the subdivided deck are hinged or otherwise secured to each other and to the sides of the boat so as to open out by gravity when the boat heels over into a 15 dangerous position.

It has already been attempted to provide decks for the protection of boats against rain and waves so as to cover the boat as completely as possible and to permit the persons in 20 the boat to get out quickly in the case of capsizing. The solutions of the problem which were proposed heretofore, however, are not satisfactory as the deck is not removed as readily or as rapidly as required 25 in case of emergency, for such devices require being operated and it is not to be expected that the persons in the boat will have the presence of mind to operate them in time, or they are automatic but are liable to become 30 fouled.

These drawbacks are eliminated in my invention which provides an absolutely reliable safety appliance for the purpose specified, which requires no operation and may be connected 35 with the boat merely by gravity or by hinges which can be relied upon to operate under all conditions.

Preferably the parts or flaps constituting the deck are merely connected with each 40 other by a butt joint so that they will open out freely upon capsizing and without being acted on by the weight of the persons in the boat. The flaps may be subdivided transversely and longitudinally. Longitudinal subdivision enables the boat to be used in completely closed, completely open or partly 45 open condition. Those flaps which are not required, may be folded down against the sides of the boat or, in a preferred embodiment, 50 erected to constitute a wash board.

Due to the ready detachability of the flaps the holds which in normal boats are only accessible through a small hatch or flap in the deck or the sides of the boat, become accessible throughout so that they are utilized 55 to the best advantage. The flaps may be made in any suitable form and of any suitable material, for instance wood or metal, preferably a light metal or alloy. They may be arched or flat, and may be solid plates or, 60 preferably in collapsible boats, they may be frames to which a suitable cover of waterproof fabric is secured. Preferably the flaps are secured to the sides of the boat by means of hinges, and strips of flexible waterproof 65 material may be attached here, and a similar connection, if desired, including packing strips, may be provided intermediate the several panels into which a flap is subdivided.

In the drawing accompanying this specification and forming part thereto devices embodying my invention are illustrated diagrammatically by way of example.

In the drawing:

Fig. 1 is a plan view of a non-collapsible 75 boat equipped with the new safety deck.

Fig. 2 is a section illustrating a boat having flaps subdivided into three panels.

Fig. 3 is a cross-section showing the flaps abutted on the fore-and-aft line of the boat, 80 on a larger scale.

Referring first to Fig. 1, the boat is covered throughout its length by means of flaps 11, 12 and 11', 12' which are divided on the fore-and-aft line and also along transverse 85 lines as shown. Similar flaps 14 and 15 are also provided for the fore-and-aft holds so that these become very readily accessible. Preferably, those parts of the deck extending along the cockpits 13, 13' are integral with 90 the corresponding flaps as indicated at 16.

Hinges or any other suitable means may be provided for attaching the flaps to the sides 18 of the boat.

As mentioned, the flaps may be flat or 95 arched as illustrated, it being important that water striking the boat will flow down its sides.

The flaps are abutted along the fore-and-aft line so as to support each other, and suit- 100

able means such as rubber strips or the like may be provided for packing the joint without interfering with the function of the flaps. To ensure their coming apart, the flaps are 5 abutted only along a narrow face the edges being otherwise beveled. The abutting face of each flap, or one of them, may be lined with metal strips holding a strip of rubber, or other packing means.

10 Preferably, a roof-shaped deflector 22 is provided, which deflects water from the joint 20 without interfering with the opening of the flaps, and a drip rail 22' is preferably provided extending beyond the joint 20, as shown in Fig. 3.

15 If it is desired, the flaps may be folded down on the inside of the boat as shown in dotted lines in Fig. 2 so that the boat is open. In this position, the flaps do not require any considerable space.

20 In comparatively wide boats the flaps are preferably subdivided longitudinally and the several panels constituting a flap are connected by hinges. This arrangement not only 25 involves the advantage that the space required for the folded-down flaps is reduced as compared with undivided flaps but, and this is most important, the open area of the boat may be varied as desired.

30 In the boat illustrated in Fig. 2, each flap is subdivided into three panels, the two inner panels being weighted as indicated at 26. The panels are shown completely folded against the side of the boat at the right and 35 partly folded at the left so as to form a wash board 24' from the overlapped edge of the panel 24.

40 I wish it to be understood that I do not desire to be limited to the exact details of construction shown and described for obvious modifications will occur to a person skilled in the art.

I claim:—

45 1. A boat comprising a deck consisting of flaps supported on the side of the boat and abutted along their inner edges, said flaps being subdivided into panels, and hinges connecting said panels.

50 2. A boat comprising a deck consisting of flaps supported on the side of the boat abutted along their inner edges and subdivided into panels overlapping each other.

55 3. A boat comprising a deck consisting of flaps supported on the side of the boat abutted along their inner edges and subdivided into panels overlapping each other, and means for placing one of said panels into such position with respect to the other that its overlapping edge constitutes a wash board.

60 4. A boat comprising a bottom and side walls, a cover resting on the top edges of said side walls and being subdivided in the longitudinal middle line thereof to form two independent halves capable of swinging in opposite directions around said top edges, each 65

half consisting of two hingedly connected longitudinal parts.

5 5. A boat comprising a bottom and side walls, a cover resting on the top edges of 70 said side walls and being subdivided in the longitudinal middle line thereof to form two independent halves capable of swinging in opposite directions around said top edges weights being secured to each half near the inner edge thereof.

6. A boat comprising a bottom and side walls, a cover resting on the top edges of 75 said side walls and being subdivided in the longitudinal middle line thereof to form two independent halves capable of swinging in 80 opposite directions around said top edges and water deflecting means secured to one of said halves near the inner edge thereof.

In testimony whereof I affix my signature.

HUGO BROCK.
